Primary Examiner — George D Kirschbaum*Assistant Examiner* — Clese Moore, Jr.(74) *Attorney, Agent, or Firm* — Shaun J. Fox(57) **CLAIM**

The ornamental design for a tire off-shoulder, as shown and described.

DESCRIPTION

FIG. 1 is a side perspective view of a tire off-shoulder showing our new design, the opposite side being identical thereto;

FIG. 2 is a side elevational view thereof;

FIG. 3 is a front elevational view thereof, the opposite side being identical thereto; and,

FIG. 4 is an enlarged fragmentary front elevational view thereof.

In the drawings, the broken lines depict environmental subject matter only and form no part of the claimed design.

1 Claim, 4 Drawing Sheets(56)
